MAGAZINE FOR SAFETY RAZOR BLADES

Joseph Muros, Cambridge, Mass., assignor to Gillette Safety Razor Company, Boston, Mass., a corporation of Delaware

Application July 3, 1943, Serial No. 493,344

13 Claims. (Cl. 206—16)

This invention consists in a new and improved magazine for safety razor blades of such construction that it may be used by the manufacturer as a commercial package for dispensing blades and discarded by the user after it has served its purpose. The invention includes within its scope the novel protected blade unit upon which the advantageous use of the magazine largely depends. The invention includes also the novel dispensing package resulting from the combination of the magazine and a stack or charge of protected blade units.

Safety razor blades are manufactured from thin sheet steel and are provided with a shaving edge or edges so sharp and keen that they are necessarily of very delicate structure. In presenting such blades to a razor they are very likely to be dulled by contact with a container or even by being drawn across their own wrapper so that the most skillful grinding and sharpening operations of the manufacturer are sometimes brought to naught. Blade manufacturers have for many years endeavored to provide metal magazines in which such blades might be safely and satisfactorily dispensed but the extreme thinness of the blades has necessitated very accurate dimensions in such magazines and rendered them too expensive to be discarded by the user. A great many unsuccessful attempts have been made to provide metal magazines of inexpensive construction but none of these has been satisfactory for the reasons pointed out. If not designed with great accuracy there is always danger of two thin blades jamming in the exit slot of a metal magazine and when this occurs the user almost invariably cuts himself in trying to free the jammed blades.

The object of the present invention is to provide an improved blade magazine or a blade unit and magazine combination in which the magazine may be constructed of cardboard or other inexpensive and deformable material so that it may be discarded after use, like an empty match box, but from which single blades may be accurately and reliably withdrawn with their sharp edge or edges fully protected against being dulled and the user's fingers fully protected against being cut. To this end an important feature of the invention consists in increasing the thickness of each blade unit by associating the blade with a filler or lining blank, thus making a protected blade unit of such thickness that it may be handled safely and conveniently and whose thickness eliminates the necessity for close limits in the

magazine structure and in the feeding mechanism thereof.

The filler piece or liner may be associated with the blade in any convenient and suitable manner so long as it overlies and shields the sharp edge or edges of the blade, imparts substantial thickness to the unit and furnishes an edge of substantial thickness for engagement by the feed slide. The filler piece may be of cardboard, fibre or other non-metallic sheet material and may be united directly to the blade by interlocking tongues or by cement or it may be united to the blade by means of a wrapper partially enclosing these elements. In either case the filler piece shields the sharp edges of the blade and provides for the protecting blade unit unsharpened guiding edges by which the unit may be directed out of the magazine and if desired into the safety razor. The filler piece also serves the function of locating the blade in its container or magazine with its sharp edges safely spaced from the walls of the magazine and this obviates the necessity of providing in the magazine locating ribs for that purpose.

The filler piece and the wrapper if used, are so designed that the usual blade-locating slot or aperture of the blade itself remains fully exposed and accessible in the protected blade unit with the result that the unit may be presented to a safety razor and delivered fully to shaving position with its protection intact. Then, when so located, the user may strip off the wrapper with the cardboard blank leaving the blade in a position within the safety razor where it is entirely safe from danger or damage.

The invention is herein shown in its application to blades of the open-end type, that is to say, a blade having a medial longitudinal slot opening through one unsharpened end edge. Such blades have the advantage that they may be presented endwise to a safety razor without the necessity of actually detaching the blade clamping members. A further feature of the invention, therefore, consists in an open-end blade in combination with a filler piece overlying the sharp edges of the blade, together with a removable wrapper enclosing the blade and filler piece and forming therewith a self-contained unit with thick unsharpened marginal edges.

These and other features of the invention will be best understood and appreciated from the following description of a preferred embodiment thereon selected for purposes of illustration and shown in the accompanying drawing, in which:

Fig. 1 is a view in perspective of the cardboard

blank from which the outer sleeve member of the magazine enclosure is formed;

Fig. 2 is a similar view of the blank from which the inner member of the magazine enclosure is formed;

Fig. 3 is a view in perspective showing the blank of Fig. 2 shaped ready for insertion into the sleeve of Fig. 1;

Fig. 4 shows the two blanks assembled in forming the magazine;

Fig. 5 is a view in perspective of the feeding member;

Fig. 6 is a view in perspective of the blank for forming the end band of the magazine;

Fig. 7 is a view in longitudinal section on an enlarged scale of the loaded magazine;

Fig. 8 is a view in perspective on an enlarged scale of a protected blade unit; and

Fig. 9 is a view in perspective of the complete blade-dispensing package.

The construction of the magazine or blade unit container will first be described. It comprises an outer sleeve and an inner tray member. The outer sleeve is readily constructed from a flat rectangular blank of cardboard or the like as shown in Fig. 1. This is longitudinally scored to define a bottom panel 10, two side panels 11 and two top wall portions 12. When this blank is folded it forms an elongated rectangular enclosure of the character shown in Fig. 4 in which the panels 11 form the vertical sides of the enclosure and the top portions 12 are inturned and spaced apart by a longitudinal slot designed to receive and guide a feed slide, as will presently appear.

The inner tray member may similarly be formed from a flat cardboard blank of the character shown in Fig. 2. This is scored to define a bottom panel 13, two side flanges 14 and end extensions 15 and 17. The end extension 15 is scored transversely to define four narrow panels and in the second of these is formed a substantially square opening 16. The other end extension 17 is also transversely scored to form four narrow transverse panels. The tray member is folded as shown in Fig. 3, that is to say, the side flanges 14 are turned up vertically, the scored extension 15 is folded to form a rectangular hollow flange having an opening in its top surface and the scored extension 17 is folded to form a similar unperforated hollow flange. The height of the side walls 14 and of the flange 15 is such as completely to fill the outer sleeve member, while the height of the platform provided by the hollow flange 17 is such as to leave a blade exit or outlet slot 18 between its surface and the inner surface of the top portions 12 of the outer sleeve, as shown in Fig. 4.

The magazine is completed by slipping the feed slide 21 into the longitudinal slot between the top wall members 12 and by closing the exit end of the magazine by means of the band 20 which, as shown in Fig. 6, is scored so that it may be folded accurately to the contour of the magazine enclosure and then cemented in place.

The feed slide 21 herein shown is moulded in integral form from plastic material and is provided with undercut or dovetailed guideways which receive the edges of the slot formed by the top wall members 12. Its lower surface is provided with a transverse shoulder 22 so that it may simultaneously engage the end of a blade unit and its adjacent upper face as will also be described hereinafter. The left end of the magazine enclosure is closed by a paper panel 23 hav-

ing a row of perforations in line with the outlet through which the advancing blade will break its way in being ejected.

The blade unit itself is best shown in Fig. 8. The blade selected for illustration is one of the well-known "Gillette" type but it is understood, of course, that the invention is not limited to that or to any other particular type of blade. The illustrated blade 25, however, is of thin flexible steel and may be as thin as .004". It is notched at each corner to define in the blade elongated unsharpened end portions and is provided with a central longitudinal slot 26. In the illustrated blade the slot is shown as opening out through one end of the blade and is enlarged into a central aperture 27 and other intermediate apertures somewhat wider than the slot 26.

The filler piece or liner 28 may be of cardboard or the like and preferably of substantial thickness, for example, twice or three times as thick as the blade itself. The filler piece is approximately co-extensive in area with the area of the blade and protects its sharp edges by overlying them, that is to say, the filler piece is slightly wider than the overall width of the blade with which it is to be used. The filler piece is forked and has a longitudinal slot of such dimensions as fully to expose the slot and apertures of the blade. As seen in Fig. 8 the inner edge of the slot in the filler piece 28 corresponds substantially with the full width of the aperture 27 in the blade. At its forward end the filler piece 28 substantially registers with the shoulders of the blade itself, while at its rear end it is provided with a shouldered portion 29 that extends substantially beyond the end of the blade. The blade 25 and its overlying filler piece 28 are herein shown as bound together in the form of a self-contained unit by a wrapper 30 which is also forked or slotted so that it will not obscure the blade slot. The wrapper is folded over the forward shoulders of the blade and the filler piece, extending on both sides of the package and having ears or tabs 31 at its rear end which are folded inwardly over the shouldered end portion 29 of the filler piece. The wrapper 30-31 may be of waxed paper, tinfoil, or any other relatively fragile sheet material which may be folded readily and secured in place by cement or otherwise.

Generally the protected blade unit will be presented intact to the safety razor and anchored therein by a blade-locating rib or detent. While thus held the user will strip the wrapper from the blade by merely pulling it endwise and breaking the wrapper where it passes over the forward shoulders of the blade. If the user desires to expose the blade before placing it in his razor he may merely grasp the exposed forward end portion of the blade 25 and strip the wrapper in the manner already suggested.

It will be understood that, as constructed of cardboard or the like, the magazine herein described is somewhat compressible or deformable, although it is reenforced throughout substantial areas by the hollow transverse flanges 15 and 17 of the inner member. Variations in the dimensions of the magazine caused by handling, however, unfit it for dealing directly with thin blades and it is only by providing blade units of substantial thickness and bulk that accurate and satisfactory feeding of the blades is achieved in the structure disclosed. In this connection the stepped feed slide 21 is of importance because it is so arranged as never to leave the blade stack,

that is to say, the feed slide never passes completely off the uppermost blade but always over-hangs it to some extent. As will be seen from Fig. 7 no amount of collapsing pressure on the magazine can upset the positive feeding engagement of the shoulder 22 with the blade unit.

In Fig. 7 the magazine is shown as containing only two blade units but in practice the magazine may contain four to ten or more of these units, and the stack is at all times pressed upwardly against the top of the magazine by a bowed spring 18 which is provided at one end with spurs that enter the bottom panel 13 of the tray member and hold the spring against displacement.

The dispensing package is shown in Figs. 7 and 9 as being in readiness to deliver a blade unit by movement of the feed slide 21 toward the left. It will be understood that the aperture 16 in the transverse hollow flange 15 permits the feed slide to pass over the inner wall of the flange and to be stopped against its outer wall. In this position the shoulder 22 is located opposite to the uppermost blade unit. When the feed slide is now advanced that unit passes over the platform of the flange 17 and breaks its way out through the perforated end panel 23. The feed slide is stopped by engaging the end band 20 and the blade unit is projected through the outlet slot so that it may be directly located in a safety razor or grasped conveniently by the user.

Having thus disclosed my invention and described in detail an illustrative embodiment thereof, I claim as new and desire to secure by Letters Patent:

1. A protected blade unit comprising a thin, sharp-edged blade having a longitudinal slot therein opening through the contour of the blade at one end, a flat filler piece co-extensive with the sharp edges of the blade, and a fragile wrapper binding the blade and filler into a self-contained unit in which the open end of the blade slot is freely accessible.

2. A protected blade unit comprising a thin sharp-edged blade having a blade-locating aperture therein, a forked filler piece at least as thick as the blade superposed thereon, overlying the sharp edges of the blade and forming a guide for the blade, and a removable wrapper enclosing the blade and filler piece and forming therewith a self-contained unit with thick unsharpened marginal edges, the filler-piece and wrapper leaving the blade aperture fully exposed.

3. A package for dispensing thin flexible razor blades, having in combination, an elongated compressible cardboard enclosure provided with a blade-exit slot in one end, a filling of protected self-contained blade units, each unit comprising a blade, a cardboard blank substantially co-extensive with the blade area and of greater thickness than the blade, and a wrapper binding the blade and blank together, and a feed slide movable in the enclosure and having a shouldered blade-engaging face, whereby the slide is limited to engagement with a single unit regardless of compressing pressure on the package and is thus adapted to advance only one unit at a time out through the blade-exit slot.

4. A package for dispensing thin sharp razor blades, having in combination, an elongated deformable cardboard enclosure provided in one end with an outlet slot, and a stack of protected blade units filling the enclosure, each unit comprising an open end blade, a filler piece overlying the sharp edges of the blade and recessed to

expose the open end of the blade, and a wrapper binding the blade and filler piece into a self-contained unit in which the outer edges of the filler piece constitute guides for directing the unit in passing through the said outlet slot, the wrapper being also recessed to expose the open end of the blade.

5. A package for dispensing thin sharp razor blades, having in combination, an elongated enclosure deformable under pressure and provided in one end with an outlet slot, and a stack of protected blade units filling the enclosure, each unit comprising a thin blade, a thicker filler overlying sharp edges of the blade and an unsharpened end portion of the blade, and a wrapper, together with a feed slide movably mounted in the enclosure and having a step in its lower surface whereby it may engage the end edge of a blade unit and the adjacent upper surface thereof.

6. A container for protected blade units, comprising an outer sleeve member having a longitudinal slot therein, an inner tray member having a transverse platform at each end, one of which closes one end of the outer sleeve and the other of which forms an outlet slot with the end of said outer sleeve, and a feed slide movable in the slot of the latter.

7. A container for protected blade units, comprising an outer sleeve member having spaced top wall portions separated by a longitudinal slot and having open ends, an inner tray member having a transverse tubular flange at each end providing between them space for a stack of blade units, a feed slide movable in said longitudinal slot, a band closing one end of the slot, and the other end being closed by a tubular flange of said tray member.

8. A container for protected blade units, comprising an outer sleeve of deformable material having a guide slot, an inner tray member having a hollow flange of rectangular cross-section at each end fitting within the sleeve, a spring for pressing a stack of blade units toward the top of the container, and a feed slide therein having a shouldered face for engaging simultaneously one end and the adjacent upper surface of a blade unit in the stack.

9. A container for protected blade units, comprising an outer sleeve of rectangular cross-section, and an inner tray member resting on the bottom of the sleeve and provided at each end with a box section flange, one flange closing one end of the sleeve and the other flange co-operating with the sleeve to provide an outlet slot at the other end of the sleeve.

10. A package for dispensing thin sharp razor blades, having in combination, an elongated substantially rectangular enclosure of deformable material provided at one end with an outlet slot, and a stack of protected blade units filling the enclosure, each unit comprising a thin blade and a thicker non-metallic filler piece overlying the sharp edges of the blade and united to the blade, whereby its edges are shielded and unsharpened edges are supplied to the unit by which it may be guided out of the enclosure through said outlet slot, and a feed slide movable in said enclosure.

11. A blade magazine comprising an elongated enclosure of yielding material having an end outlet and longitudinal slot in its upper wall, and a feed slide movable in said slot and having a shouldered blade-engaging face, whereby the slide is limited to engagement with a single blade

regardless of compressing pressure on the magazine.

12. A blade magazine comprising an outer sleeve of rectangular cross-section, an inner member having transverse hollow flanges at both ends which reenforce the outer sleeve in spaced areas, and a feed slide movable in a path between said transverse flanges.

13. A protected blade unit comprising a thin flexible sharp-edged blade provided with a cen-

tral longitudinal slot opening out through one end of the blade, a forked filler piece at least as thick as the blade superposed thereon, overlying the sharp edges of the blade and forming a guide for the blade, and a removable wrapper enclosing the blade and filler piece and forming therewith a self-contained unit with thick unsharpened marginal edges, the filler and wrapper leaving the blade slot fully exposed.
